UNITED STATES PATENT OFFICE.

GEORGE H. LITTLE, OF WINSTON-SALEM, NORTH CAROLINA, ASSIGNOR TO R. J. REYNOLDS TOBACCO COMPANY, OF WINSTON-SALEM, NORTH CAROLINA, A CORPORATION OF NEW JERSEY.

MACHINE FOR APPLYING BOX TOPS.

1,419,576.

Specification of Letters Patent. Patented June 13, 1922.

Application filed May 27, 1921. Serial No. 473,105.

To all whom it may concern:

Be it known that I, GEORGE H. LITTLE, a citizen of the United States, and resident of Winston-Salem, in the county of Forsyth 5 and State of North Carolina, have invented certain new and useful Improvements in Machines for Applying Box Tops, of which the following is a specification.

My invention relates to mechanism for 10 applying tops to boxes and like containers.

The general object is to provide simple and accurately operating mechanism capable of applying tops to box bodies in rapid succession.

15 A more particular object is to provide means for supporting and advancing the box tops in groups, and more especially in partially nested stacks, and successively withdrawing individual tops from the group or 20 stack and applying them to box bodies which are successively presented at the application point.

A further object is to provide means for advancing successive groups or stacks of the 25 tops, so that while the tops are being applied from one stack another is adjacent to it and ready to move into position as soon as the tops in the first stack are exhausted.

Another object is to provide improved applying mechanism of very simple character, 30 adapted to the preferred mode of top-stack arrangement.

Another object is to provide means for detecting failure of the machine to apply a 35 top to an advancing box body, because of exhaustion of the supply of tops at the application point, or for other reasons, and desirably to provide means in connection with this detecting mechanism for indicating in 40 some noticeable way the failure of top application so that the attendant can take necessary steps to remedy the difficulty.

The invention, therefore, provides means 45 for accomplishing these and other objects, as sufficiently described hereinafter.

The accompanying drawing shows one exemplifying embodiment of the machine, and after considering this in connection with the 50 description it will be understood that many variations may be made in the organization of the machine, and in parts and sub-combinations of parts, within the principles of the invention; also that certain subordinate parts of the mechanism have utility in them-

55 selves, as well as in the complete machine as herein shown. I, therefore, do not limit myself to the precise structure shown, but contemplate any structures which are properly within the scope of the appended claims.

In the drawings:

60 Figs. 1 and 1^a taken together are a side elevation of a machine embodying my invention.

Figs. 2 and 2^a taken together are a top plan.

65 Figs. 3 and 3^a are an enlarged side elevation of the central portion of the machine as seen in Figs. 1 and 1^a.

Fig. 4 is an enlarged top plan near the 70 left-hand end of the machine showing especially box body supply or feeding means.

Fig. 5 is a side elevation of top omission detecting and signalling mechanism.

Fig. 6 is a section of Fig. 5 on the line 75 6—6.

The mechanism is conveniently organized about a longitudinal table 1, which is usually supported by standards or legs, not shown. The table is longitudinally apertured or channeled to receive the upper stretch of a 80 conveyor chain 2. This chain passes about sprockets 3 and 4, carried by shafts 5 and 6, located below the table and conveniently supported in bearings 7 fixed to the under surface of the table. The sprocket shaft 85 5 in the present instance is the driving shaft, and this is driven in any suitable way from any convenient source of power.

At regularly spaced intervals the conveyor chain is provided with lugs or short transverse cleats 8 which engage and forward the 90 box bodies B. The upper stretch of the conveyor chain is supported in any convenient way, for instance, by the bottom of the channel formed in the table or by inwardly 95 projecting edges of the table aperture, when the table is apertured; or otherwise the active stretch of the chain may be supported by the ends of the cleats 8 which project over the upper surface of the table adjacent 100 to the channel or aperture which accommodates the chain.

The box bodies B may be placed on the conveyor by hand at the feed end of the machine or may be positioned by any suitable automatic or semi-automatic device. 105 In the present embodiment of the invention the particular means employed for placing

the bodies on the conveyor comprises the following: A shelf 10 is arranged to extend laterally from the table with its upper surface flush with the table surface. At one 5 side this shelf has an upwardly projecting guide rail 11, and near the other side of the table a co-operating guide rail 12 is provided, consisting in this case of a strip of material arranged convergently with respect 10 to guide rail 11 in the direction of the table. A row of box bodies B is shown in position on shelf 10. In the present instance the machine is adapted for handling relatively long and narrow box bodies of rectangular form, 15 and such boxes are well adapted to contain such commodities as packages of cigarettes arranged in rows and tiers, in the present instance two superposed rows of packages, with five packages in each row. Evidently 20 the mechanism may be arranged to handle boxes of widely divergent proportions and form, which may be filled with various commodities and, of course, the machine will operate equally well when desired with empty 25 boxes. The boxes may be placed without particular care upon the shelf 10 and as they are advanced toward the conveyor chain they are properly positioned against the 30 guide rail 11 by the convergent guide rail 12. The boxes may be passed over the shelf 10 by a pusher or by a conveyor belt, or by hand operation, as may be desired. In any 35 case they are moved so that a box body is advanced over the conveyor chain in front of each advancing lug 8 and thereafter the bodies are carried forward by the conveyor between vertical guide rails 14 and 15 at the sides of table 1. Guide rail 15 is usually 40 extended forward so that it is opposite the line of box bodies on shelf 10 and serves to limit the advance movement of the successive boxes as they are placed on the conveyor. The forward end of the other guide rail 14 desirably has an outwardly flared 45 portion 16 to assist in properly locating the boxes as they are advanced by the conveyor.

Shortly after the boxes are placed upon the conveyor they are desirably brought under a longitudinal upper guide rail or strip 20 which is supported by frame members 21, with their upright members secured to the table. This guide strip has an angular relation to the table so that as the boxes advance the guide strip confines them more closely and finally, as they approach the point of top application the guide strip is arranged to provide only slight clearance above the upper edges of the body and any 50 possibility of the bodies moving away from the table adjacent to the point of top application is prevented.

The box tops T are in the present case of rectangular form to correspond with the 55 shape of the bodies, and are of a size to fit

snugly down over the bodies, and they are desirably arranged prior to application, as best shown in Fig. 3, in groups or stacks, and more especially are partially nested together so that one end of each top is inserted 70 within the end of the top next above it and the successive tops in the stack are progressively tilted in relation to the substantially horizontal position of the lowest top. Otherwise described, the tops are in a partially nested fan-like formation, each top 75 having one end entirely free and with its open edge resting upon the closed upper surface of the next lower top in the stack. A stack of tops so arranged is supported adjacent to the application point by a longitudinal, horizontal shelf 25, whose rearward end terminates slightly forward of the rear end of guide strip 20. The tops are further 80 confined in a housing comprising vertical side plates 26 and a rear end plate 27, which has its main portion inclined at a moderate angle to the vertical down to a point 28 where the plate is bent to form a horizontal portion 29 terminating at 30. 90 The portion 29 of the plate or strip 27 may be supported by yoke members 31 similar to the yoke piece 21 previously described.

The construction and arrangement of the housing, shelf 31 and guide strip 20 are 95 such that an aperture is provided between the rear end of strip 20 and the lower end of angular guide plate 27 to permit positioning of successive tops for initial application to the advancing box bodies. In Fig. 100 3, the parts are shown just after the initial engagement of the lower top in the stack with an advancing body. The upper edge of the forward end of the box body has entered the open bottom of the top section and has engaged the forward end of the top section and has commenced to pull this top section out from the stack; and this movement has progressed to such an extent that the advancing end of the top section has 105 been brought under the adjacent end of the horizontal guide strip 29. As this movement continues the withdrawal of the top from the stack is completed and the upwardly curved portion of the said adjacent end of guide plate 29 presses the box top down into initial engagement with the body throughout the entire circumference of the box parts. As this initial assembly is completed the forward end of the top section is withdrawn from the rearward end of the top section next above it in the stack, and the stack drops down and the top T which is 110 now lowest in the stack lies at such an angle in the aperture that its forward edge is in the line of movement of the next advancing box body, and the operations are repeated 115 indefinitely until the tops in the stack are exhausted. The frictional engagement of the partially nested top sections causes the stack 120 125 130

to advance against the angular guide plate 27, as sufficiently understood from Fig. 3 without elaborate explanation.

It is desirable to provide means for quickly, and preferably for automatically replacing an exhausted stack of tops with a fresh stack in proper arrangement. For this purpose a stack feed belt 35 is provided, carried by belt pulleys 36 and 37 mounted on shafts 38 and 39, and these shafts are supported in bearings in vertical brackets 40, secured to the table. For the proper adjustment of feed belt 35 the brackets 40 which support its forward shaft 38 may be pivotally mounted at 40^a and provided with arc-shaped slots 40^b through which a bolt 40^c passes. The brackets may be rotated about the pivot center 40^a to adjust the belt and the adjustment secured by tightening bolt 40^c. Shaft 39 is conveniently driven at suitable speed from a shaft 5 by pulleys and a belt 41. The vertical side plates 26 are extended forward to substantially embrace the active range of feed belt 35. While box tops are being fed from the stack positioned adjacent to the applying opening, a fresh stack is placed on the upper stretch of conveyor 35, and this stack is frictionally urged by the conveyor toward the active stack of tops so that the rearward end of the lowermost top in the inactive stack engages the upper surface of the uppermost top in the active stack. The frictional effect of the stack feed belt 35, therefore, assists in urging the tops in the active stack forward to application position and also carries the inactive stack forward as the active stack is depleted, until finally when the uppermost top in the active stack is drawn away through the application opening, the inactive stack is moved forward over shelf 25 and into active position, and tops are then fed from the newly positioned stack in the manner previously described. Mean time the attendant places a new stack of tops on the feed belt 35, and the cycle of operations continues indefinitely.

It is desirable to arrange the side plates 26 with converging portions 45 to accurately center the tops substantially at the point of application and the box body guide rails 14 and 15 may also be provided at substantially the same point with converging portions to center the bodies in a similar manner.

To the rear of horizontal guide plate 29 means are provided for completing the application of the tops, that is for moving the tops down into complete telescoped relation with the bodies. Such means comprises in the present embodiment a guide plate 50 inclined downward in the direction of box advance. The forward end of this plate may be pivoted at 51 in uprights 52 and the rearward end may be somewhat upwardly curved as at 53, and urged downward by springs 54 connected at their lower ends to the table and at

their upper ends to a cross piece 55 secured to the guide plate 50 near the point 53. As the boxes come under guide plate 50 downward pressure is exerted on the tops and they are gradually moved down into final 70 position by the yielding pressure of the angular guide plate which will, if a cover unduly resists the emplacing movement for any reason, move upwardly sufficiently to prevent damage to the machine or breakage of 75 the box body or top.

It is desirable in some cases, and means are included in the invention for detecting the absence of a top at a suitable point in the advance of the box bodies, for instance, after 80 the bodies pass the point at which application should be made. A top may be absent because of failure to replenish the stack of tops at the proper time, or by failure of the stack to feed forward properly, or for some 85 other reason. It is desirable to detect such a failure. Desirably, also in connection with a suitable detecting device, means are provided for signalling to the attendant so that the difficulty may be remedied. 90

The detecting and signalling mechanism shown in detail in Figs. 5 and 6 comprises bars 60 and 61 hinged or pivoted at the points 62 to a suitable side member, such as the vertical extension 64 of guide rail 14 95 previously referred to. These bars are acted upon by a cross piece 66, the ends of which overlie the respective bars 60 and 61 and the central part of which is engaged by a spring 67 compressed against the cross piece by a 100 spring bolt 68 the inner end of which engages with a side member of the frame, such as vertical rail extension 64. Near their free ends the bars 60 and 61 are pivotally connected at the points 69 to an upright lever 70. 105 At the lower end the lever has an inturned member or toe 71 adjacent to the outer surface of guide rail 14. The bars 60 and 61 are also provided with members 75 and 76 arranged to project inward through slots in 110 guide rails 64 and 14 and slidably engage the adjacent side surfaces of passing box tops and bodies, as sufficiently understood in Fig. 6.

When a box passes with a top properly in 115 position as shown in this figure, the lever is held in substantially upright position against the action of spring 67; but if a top is absent from the passing box for any reason, the top engaging member 75 is permitted to move inward and the upper end of the lever at the same time is moved inward by the action of spring 67. This movement of the lever constitutes in a broad sense a detecting and indicating action. To effectively 120 signal to the attendant, however, a suitable signal is desirably arranged to cooperate with the lever. Such signaling mechanism comprises in the present instance a sliding contact member 80 arranged to reciprocate 125

130

in a block of insulating material 81, and this bolt-like contact member may be provided with a resetting handle 82 projecting upward through a slot 83 in the insulating 5 block. The inner end of the contact member 80 is arranged to make contact with a flexible fixed contact member 85 mounted on an insulating block 86. The blocks 81 and 86 may conveniently be mounted on a plate 10 88, and this in turn may be located on horizontal guide strip 29 previously mentioned, and the insulating blocks and associated mechanism may be enclosed by a housing or shield 90 which also may be provided with 15 a slot 91 to accommodate resetting handle 82. The contact members 80 and 85 are connected in a circuit 95 including a source of electrical energy such as battery 96, and a signaling device 97, in the present case an 20 electric bell. The outer end of sliding contact member 80 is in line with the upper end of lever 70, so that when the lever moves inward upon the omission of a top as previously described, the contact member 80 is 25 moved over and the circuit is closed through contact 85 and the bell rings, warning the operator of the omission of a top, and the necessary steps may then be taken to correct the difficulty.

30 I claim:

1. Box top applying mechanism, comprising means for advancing box bodies successively to a top applying position, means for maintaining a group of partially nested 35 tops substantially at the top-applying position, and means for supplying successive tops from the group to successively positioned bodies and successively advancing the group to position another top for application after each top is withdrawn.

2. Box top applying mechanism, comprising means for advancing box bodies successively to a top applying position, means for maintaining a stack of tops substantially at 45 the top-applying position, and means for supplying successive tops from the stack to successively positioned bodies and for advancing the stack to position another top for application after each top is withdrawn, said 50 means comprising an angularly arranged guide-plate controlling the advancing movement of the stack.

3. Mechanism for applying tops to boxes, comprising means for advancing box bodies 55 successively to a top applying point, means for maintaining a stack of box tops adjacent to the application point with the lowermost top in the stack in application position and for advancing the stack to continually position the lowermost top in the stack as the tops are successively withdrawn, and means for advancing another stack of tops toward applying position as the stack in applying 60 position is exhausted.

65 4. Mechanism for applying tops to boxes,

comprising means for advancing box bodies successively to a top applying point, means for maintaining a stack of partially nested box tops adjacent to the application point with the lowermost top in the stack in application position and for advancing the stack to continually position the lowermost top in the stack as the tops are successively withdrawn, and means for advancing another stack of similarly arranged tops as 70 the stack in applying position is exhausted.

5. Mechanism for applying tops to boxes, comprising means for advancing box bodies successively to a top applying point, means for maintaining a stack of box tops adjacent 80 to the application point with the lowermost top in the stack in application position and for advancing the stack to continually position the lowermost top in the stack as the tops are successively withdrawn, and means for supporting another stack of tops in a position adjacent to the stack in active position and advancing said other stack to active position as the stack in active position is exhausted.

6. Mechanism for applying tops to boxes, comprising means for advancing box bodies successively to a top applying point, means for maintaining a stack of partially nested box tops adjacent to the application point 95 with the lowermost top in the stack in application position and for advancing the stack to position the lowermost top in the stack as the tops are successively withdrawn, means for supporting another stack of similarly nested tops in inactive position adjacent to the stack in active position, and means for advancing the inactive stack to active position as the stack in active position is exhausted.

7. Mechanism for applying tops to boxes, comprising means for advancing a series of box bodies, a support for a stack of partially nested box tops, and an angular guide member engaging one end of the stack, the support and the guide member being arranged to provide an applying opening in which the tops are successively positioned from the bottom of the stack in the path of the bodies for application thereto.

8. Mechanism for applying tops to boxes, comprising means for advancing a series of box bodies, a support for a stack of partially nested box tops, an angular guide member engaging one end of the stack, the support and the guide member being arranged to provide an applying opening in which the tops are successively positioned from the bottom of the stack in the path of the bodies for application thereto, and a moving support for an inactive stack of similarly nested tops arranged to forward the inactive stack to active position adjacent to the applying opening as the active stack is exhausted.

9. Mechanism for applying tops to boxes,

comprising means for advancing a series of box bodies, a support for a stack of partially nested box tops, an angular guide member engaging one end of the stack, the support and the guide member being arranged to provide an applying opening in which the tops are successively positioned from the bottom of the stack in the path of the bodies for application thereto, and means beyond 10 the applying opening for pressing the tops into position on the bodies.

10. Mechanism for applying tops to boxes, comprising means for advancing a series of box bodies, a support for a stack of partially 15 nested box tops, an angular guide member engaging one end of the stack, the support and the guide member being arranged to provide an applying opening in which the tops are successively positioned from the bottom of the stack in the path of the bodies for application thereto, and means 20 to the rear of the applying opening for pressing the tops partially into position on the bodies, and means acting subsequently for pressing 25 the tops completely into position upon the bodies.

11. Mechanism for applying tops to boxes, comprising a conveyor for advancing a series of box bodies, a support for a stack of 30 partially nested box tops, an angular guide member engaging the rear end of the stack, the support and the guide member being arranged to provide an applying opening in which the tops are successively angularly 35 positioned from the bottom of the stack in the path of the bodies, so that in the advancing movement of the bodies successive tops are withdrawn and the stack is advanced and positioned by frictional engagement of the withdrawn top in cooperation 40 with the guide member.

12. Mechanism for applying tops to boxes, comprising a conveyor for advancing a series of box bodies, a support for a stack of partially 45 nested box tops, an angular guide member engaging the rear end of the stack, the support and the guide member being arranged to provide an applying opening in which the tops are successively angularly 50 positioned from the bottom of the stack in the path of the bodies, so that in the advancing movement of the bodies successive tops are withdrawn and the stack is advanced and positioned by frictional engagement 55 of the withdrawn top in cooperation with the guide member, and a moving support for an inactive stack of similarly nested tops arranged to forward the inactive stack to active position adjacent to the applying 60 opening as the active stack is exhausted.

13. Mechanism for applying tops to boxes, comprising a conveyor for advancing a series of box bodies, a support for a stack of partially 65 nested box tops, an angular guide member engaging the rear end of the stack, the

support and the guide member being arranged to provide an applying opening in which the tops are successively angularly positioned from the bottom of the stack in the path of the bodies, so that in the advancing movement of the bodies successive tops are withdrawn and the stack is advanced and positioned by frictional engagement of the withdrawn top in cooperation with the guide member, and means to the rear of the applying opening for pressing the tops into position on the bodies.

14. Mechanism for applying tops to boxes, comprising a conveyor for advancing a series of box bodies, means for guiding bodies to the conveyor, a support for a stack of partially nested box tops, an angular guide member engaging the rear end of the stack, the support and the guide member being arranged to provide an applying opening in which the tops are successively angularly positioned from the bottom of the stack in the path of the bodies, so that in the advancing movement of the bodies successive tops are withdrawn and the stack is advanced and positioned by frictional engagement of the withdrawn top in cooperation with the guide member, means to the rear of the applying opening for pressing the tops partially into position on the bodies, and means acting subsequently for pressing the tops completely into position upon the bodies.

15. In box top applying apparatus, in which tops are applied to successively advanced box bodies, a guiding channel, means therein for pressing the tops partly in position on the bodies, a movably mounted presser plate acting on the tops during further movement of the bodies to press the tops completely into position on the bodies, and means yieldingly urging the presser plate into contact with the tops.

16. In box applying apparatus, in which tops are successively applied to advancing box bodies, a guiding channel, means therein for pressing the tops partly in position on the bodies, a pivoted presser plate acting on the tops during further movement of the bodies to press the tops completely into position on the bodies, and a spring yieldingly maintaining the presser plate in angular position in contact with the tops.

17. In mechanism for applying tops to box bodies, a conveyor for advancing box bodies in spaced relation, means for feeding bodies successively to the conveyor, means for supporting a stack of partially interlocked box tops and for supplying tops successively from the stack to advancing bodies, and subsequently acting means for pressing the tops into position on the boxes.

18. In mechanism for applying tops to box bodies, a conveyor for advancing box bodies in spaced relation, means for guiding

bodies to the conveyor, means for supporting a stack of partially interlocked box tops and for supplying tops successively from the stack to advancing bodies, subsequently actuating means for pressing the tops into position on the bodies, and means for moving a fresh stack of tops into active position as the stack at that position is exhausted.

19. In box top applying mechanism in which tops are applied to successive box bodies, a movable member arranged to engage passing box assemblies and cooperating means for indicating the absence of a top from the body after the latter passes the application point.

20. In box top applying mechanism in which tops are applied to successive box bodies, means for detecting the absence of a top from the body after the latter passes the application point, and a signal acting in conjunction with the detecting means.

21. In box top applying mechanism in which tops are applied to successive box bodies, means for detecting the absence of a top from the body after the latter passes the application point, and an audible signal actuated by the detecting means.

22. In box top applying mechanism in which tops are successively applied to advancing box bodies and pressed partially in position thereon, a movable member arranged to engage passing box assemblies and cooperating means for indicating the absence of a top from the body after the latter passes the application point.

23. In box top applying mechanism in which tops are successively applied to advancing box bodies and pressed partially in position thereon, means for detecting the absence of a top from the body after the latter passes the application point, and a signal acting in connection with the detecting means.

24. In box top applying mechanism in which tops are successively applied to advancing box bodies and pressed partially in position thereon, means for detecting the absence of a top from the body after the latter passes the application point, and an audible signal actuated by the detecting means.

25. In box top applying mechanism in which tops are applied to successive box bodies, a member arranged to engage a box top advanced in proper position on a body, a signal, and means for actuating the signal by movement of said member in the absence of a box top from a passing body.

26. In box top applying mechanism in which tops are successively applied to advancing box bodies and pressed partially in position thereon, a member arranged to engage a box top advanced in proper position on a body, a signal, and means for actuating the signal by inward movement of said member in the absence of a box top from a passing body.

27. In mechanism of the class described, in which successive box bodies are supplied with tops and the assemblies so formed are moved on beyond the top application point, detecting mechanism comprising a member arranged to contact with a part of a top when the latter is in correct position on a body, a movable arm carrying said member, means urging the arm to engage the member with the box top, and a lever positioned in accordance with the movement of the arm.

28. In mechanism of the class described, in which successive box bodies are supplied with tops and the assemblies so formed are moved on beyond the top application point, detecting and signaling mechanism comprising members adapted respectively to engage portions of the top and body of a passing assembly, pivoted arms carrying said members, means urging the arm to engage the members with the assembly, a lever movably connected with both of the arms, and a signal operated by the lever.

29. In mechanism of the class described, in which successive box bodies are supplied with tops and the assemblies so formed are moved on beyond the top application point, detecting and signaling mechanism comprising members adapted respectively to engage portions of the top and body of a passing assembly, pivoted arms carrying said members, means urging the arms to engage the members with the assembly, a lever movably connected with both of the arms, a movable contact member operated by the lever, a relatively fixed contact member, an electric circuit including said contacts, and an electrically operated signaling device in said circuit to signal the attendant upon the passage of an incorrect assembly.

30. In box top applying mechanism in which tops are applied to successive box bodies, a signal, and means rendering the signal active upon movement of an uncovered box body beyond the top-applying point.

Signed at Winston-Salem, in the county of Forsyth and State of North Carolina, this 27th day of April, A. D. 1921.

GEORGE H. LITTLE.
